US00D646174S

(12) **United States Design Patent**
Toh et al.

(10) **Patent No.:** **US D646,174 S**
(45) **Date of Patent:** ** ***Oct. 4, 2011**

(54) **CONTAINER**

(75) Inventors: **Kiat-Cheong Toh**, Forest Hills, NY (US); **Sergio Gedanke**, Brooklyn, NY (US); **Ravi Varma**, New York, NY (US)

(73) Assignee: **Colgate-Palmolive Company**, New York, NY (US)

(**) Term: **14 Years**

(21) Appl. No.: **29/328,932**

(22) Filed: **Dec. 4, 2008**

(51) LOC (9) Cl. **09-01**

(52) U.S. Cl. **D9/542**; D9/563; D9/571; D9/574

(58) **Field of Classification Search** D9/516, D9/529-530, 537-543, 549, 550-552, 558, D9/563-565, 571, 574-575, 682-694; 215/382-384; 220/660, 662, 669

See application file for complete search history.

FOREIGN PATENT DOCUMENTS

FR DM051955 3/2000

(Continued)

Primary Examiner — Carol Rademaker(74) *Attorney, Agent, or Firm* — Judy W. Chung(57) **CLAIM**

The ornamental design for a container, as shown and described.

DESCRIPTION

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showings of threads on the neck of the container and the bottom of the container are for illustrative purposes only and form no part of the claimed design.

1 Claim, 6 Drawing Sheets
